United States Patent Office.

HIRAM W. OLNEY, OF PITTSBURG, PENNSYLVANIA.

Letters Patent No. 104,989, dated July 5, 1870.

IMPROVED METHOD OF HANGING WINDOW-SHADES.

The Schedule referred to in these Letters Patent and making part of the same.

To all whom it may concern:

Be it known that I, HIRAM W. OLNEY, of Pittsburgh, in the county of Allegheny and State of Pennsylvania, have invented a new and useful improved Mode of Hanging Window-Shades; and I do hereby declare that the following is a full, clear, and exact description thereof, sufficient to enable those skilled in the art to which my invention appertains to make and use the same, reference being had to the accompanying drawing making part of this specification, in which—

Figure 1 is a front view representing my improvement as applied to an ordinary window-shade.

Figure 2 is a side view of the same.

The nature of my invention consists in securing the shade and fixture to a cornice instead of to the window-frame, and attaching it to the window frame by means of hooks and rings.

The cornice is made with a board attached at right angles, so as to form a covering for the curtain and fixtures. Suitable brackets for the journals of the rollers are attached to the cornice, and the usual arrangement of the cord may be adopted. I prefer, however, to wind the cord around one end of the roller, as shown in fig. 1, so that, on pulling the cord, the roller is revolved and the shade rolled up, and *vice versa*.

To the top of the cornice A are attached two or more rings, B, at positions corresponding with hooks,

C, driven or screwed into the window-frame, so that the cornice, with the shade and fixtures attached, can be put in place by simply hanging the rings on the hooks.

The hooks may be inserted either in the face or in the lower side of the top portion of the frame.

My improvement facilitates the removal and replacing of curtains, and saves the trouble and annoyance of putting up and taking down fixtures, the hooks C and one or more knobs D for the cord being the only fixtures required to be attached to the window-frame.

The cornice A also protects the shade and fixtures from dust to a great extent.

I am aware that brackets and moldings have been attached to window-frames by means of hooks and rings, and therefore I do not claim, broadly, the attachment of the cornice by means of the hooks and rings; but

What I claim as new, and desire to secure by Letters Patent, is—

The cornice A, attached to the window-casing by the rings B and hooks C, and having the curtain-roller attached to the inside of the cornice, when constructed and arranged as herein shown and described, for the purpose specified.

H. W. OLNEY.
